DRIER DRAINAGE SYSTEM WITH PRESSURE DIFFERENTIAL CONTROL

Hervey G. Cram, Appleton, Wis.

Application January 21, 1953, Serial No. 332,139

8 Claims: (Cl. 34—119)

This invention appertains broadly to heating and draining systems for paper dryers of the general type shown in certain of my prior patents, such as Patents No. 1,919,416; No. 2,045,634 and No. 2,242,778 issued respectively, on July 25, 1933; June 30, 1936 and May 20, 1941.

One of the primary objects of the present invention is to effect an improvement in the efficiency of steam-filled rotating cylindrical dryers, over which and in contact with, a continuous sheet of material, such as, paper, is passing for the purpose of drying.

Steam is delivered to the individual cylindrical dryer through the dryer journal to the interior for contact with the shell of the dryer where the latent and other heat of the steam is transferred to and through the shell of the dryer to the sheet of paper with which it is in contact, and, the resultant condensate must be continuously removed, otherwise, if allowed to accumulate the condensate will cover a material portion of the interior of the dryer shell which is detrimental to the rate of drying, in that the rate of heat conductivity through water is greatly less than that of the metal of the dryer shell.

Air and other non-condensable gases with which the steam is more or less contaminated, must also be removed or maintained at the very lowest minimum accumulation possible, as a concentration at the interior surface of the dryer shell, or even as a mixture with the steam, is very detrimental to the rate of drying, in that the rate of conductivity of heat through air is greatly less than that of cast iron.

The most feasible method of removing the condensate from the dryer, is through the dryer journal with a vertical siphon drop leg pipe (see my prior patents above-mentioned), having an open inlet in close proximity to the dryer shell.

The only known method of maintaining a minimum accumulation of air and other non-condensable gases in a dryer during operation is by means of a continuous circulation of the steam through the dryer, and thereby, carrying the air and other non-condensable gases along with it, and the simplest method of accomplishing this purpose, is by ejecting a fixed minimum amount of steam along with the condensate through the siphon.

Based on the above, another salient object of my invention is the provision of means for the re-using of the latent and other heat of this steam in certain of the drying cylinders of a battery of cylindrical dryers.

A further object of the invention is to provide in a battery of cylindrical dryers, a primary section receiving its steam from the usual source of supply and a secondary section receiving its steam from the discharge of the dryers of the primary section, the arrangement being such as to create an effective pressure differential across the dryers of the primary section which is sufficient to lift the condensate up the vertical drop leg of the siphon, to and through the dryer journal, and, to circularize the steam through the dryer.

A further important object of my invention is to effect a pressure differential across the dryers of the secondary section by means of a condenser, and/or, a vacuum pump, and to maintain a fixed hydrostatic head of condensate on the intake of the pump, plus the steam pressure in the discharge line from the dryers, and thereby adding to pump efficiency.

A still further object of my invention is to regulate the flow of steam as discharged with the condensate from the primary section according to the demand of the secondary section and the demand of the condenser, and/or,

the vacuum pump, and to establish and maintain automatically the fixed, predetermined pressure differential across each individual dryer for this purpose.

A still further important object of my invention is to provide a continuous suction effect on the siphon of each dryer, so that as soon as the inlet of a siphon is condensate-sealed, discharge from the dryer will be immediately effected, thereby assuring a minimum accumulation of condensate in each dryer.

A still further important object of my invention is to provide means for visible observation of the rate of flow of condensate and steam being discharged from each individual dryer, so that such rate of discharge can be accurately determined.

A still further important object of the invention is the provision of a novel valve arrangement in the discharge portion for each dryer to establish and maintain automatically the desired, fixed pressure differential across each individual dryer.

With these and other objects in view, the invention consists in the novel construction, arrangement and formation of parts, as will be hereinafter more specifically described and claimed, and illustrated in the accompanying drawings, in which drawings,

Figure 1 is a diagrammatic view in side elevation, showing my improved system incorporated with a battery of dryers in a paper making machine.

Figure 2 is an enlarged fragmentary detail view through a portion of a dryer showing the siphon in the dryer journal, the parts in section being taken on the line 2—2 of Figure 3 looking in the direction of the arrows.

Figure 3 is an end elevational view of a portion of a dryer with parts thereof broken away and in section and illustrating the pressure differential valve, casing incorporated in the discharge line or leg of the dryer.

Figure 4 is an enlarged detail vertical sectional view taken on the line 4—4 of Figure 2 looking in the direction of the arrows illustrating the novel pressure differential valve.

Figure 5 is a horizontal sectional view through the valve taken on the line 5—5 of Figure 4, looking in the direction of the arrows.

Figure 6 is a detail side elevational view of the novel valve body employed in the valve.

Referring to the drawings in detail, and more particularly to Figure 1, I have shown diagrammatically a battery B of dryers of a paper making machine, and these dryers are of the rotating, cylindrical type, over which and in contact with which a continuous sheet of paper (not shown) is passing for the purpose of drying.

In accordance with my invention, the battery B of dryers is divided into a primary section 10 of any number of cylindrical dryers and a secondary section 11 composed of a plurality of dryers. The secondary section 11 for the purpose of illustration, includes two dryers 12 and 13 and a baby dryer 14.

Steam is supplied to the primary section 10 through a header 15 and this header is fed with steam from a supply line 16 leading from a suitable source (not shown).

Each of the dryers of the primary section 10 and the secondary section 11 is provided with a hollow journal 17, and the outer ends of all of these journals are provided with couplings 18. Connected with the couplings 18 of the dryers of the primary section 10 are feeder pipes 19, branching off of the header 15. Connected with the couplings 18 of the dryers of the secondary section 11 are feeder pipes 20, which will be later referred to.

The water of condensation and air and other non-condensable gases from the various dryers of the primary, 70 and secondary sections 10 and 11, are removed by siphons 21 (see my patent No. 2,617,205, issued November 11, 1952). Each siphon 21 includes a horizontal section 22 which extends through the steam joint or coupling 18 and the inner siphon or drop leg 23. The lower end 75 of the siphon leg 23 is provided with the inlet head 24.

Extended along the battery B of drying cylinders is a condensate header 25, and coupled with this header are the outer siphon legs 26 for the dryers of the primary section 10 and the outer legs 26 are coupled with the horizontal section 22 of the siphons for the primary section. The horizontal section 22 of the siphons 21 for

the dryers of the section 11 have coupled therewith outer legs 27. These legs 27 are all connected with a secondary header 28 for condensate. The feeder pipes 20 for the dryers of the secondary section 11 are all connected with the main condensate header 25.

Briefly, from the description so far, steam is supplied to the dryers of the primary section 10 from the header 15 and the condensate and gases are removed from these dryers to the header 25, and this header, in turn, supplies the dryers of the secondary section 11 with steam for heating these dryers and the condensate and gases from the dryers of the secondary section 11 are removed by the siphons of these dryers and delivered to the secondary header 28 for condensate. Thus, heat from the steam removed from the dryers of the primary section is utilized again for heating the dryers of the secondary section and this forms an important feature of my invention.

As brought out in the objects of this specification, one of the main features is to create an effective pressure differential across the dryers of the primary section 10, so as to lift the condensate up the vertical drop leg 23 of each dryer in the primary section and to circulate the steam through each dryer and to regulate the flow of steam as discharged with the condensate from the primary section to the demand of the secondary section and to establish and maintain automatically a fixed predetermined pressure differential across each dryer. This is essential, in that, drying conditions are continuously changing owing to the variations in the sheet being dried, such as, moisture content, weight of the sheet, etc.

In order to accomplish these purposes, I provide in each outer drop leg 26 of the dryers of the primary section 10, and each outer drop leg 27 of the dryers of the secondary section 11, a pressure differential control valve 29, and this valve is best shown in Figures 4, 5 and 6, and will now be described in detail.

Each valve 29 includes a casing 30, preferably formed in an upper section 31 and a lower section 32 for ease in manufacture and assembly, and these sections 31 and 32 are united in fluid tight relation by bolts 33. Formed in the casing 30 is an inner valve chamber 34 provided at its lower end with a valve seat 35 forming an inlet and at its upper end with an outlet opening 36. Communicating with the valve seat 35, is an outer passageway 37 into which flows the condensate and make-up steam. Communicating with the opening 36 is an outer passageway 38, which leads to the discharge section of the outer drop leg. Directly above the opening 36 in the valve chamber 34 is an orifice 39 formed in the interior division wall of the passageways 37 and 38, and this orifice is also disposed directly below the inlet of the casing 30 for the condensate and make-up steam.

Slidable and rotatable within the valve chamber 34 is a valve body 40 and formed on the valve body are radially extending vertical guide ribs 41, which space the valve body proper from the wall of the valve chamber 34. The lower end of the valve body is tapered, as at 42, for fitting snugly on the valve seat 35, when the valve is in its closed position. The lower ends of the guide ribs 41 are tapered or beveled on one side, as at 43, and water of condensate impinging on the faces 43 tends to turn the valve body for the purpose of insuring the seating of the valve body and to increase the noticeability of the body when viewed through a sight glass 45 carried by one side of the valve casing 30. The provision of this sight glass not only enables an observer to view the functioning of the valve body but to also visibly determine the flow of condensate through the valve casing.

This pressure differential control valve 29 functions as follows: condensate, surplus steam, air and other non-condensable gases are delivered through the siphon inlet 24 to and through the siphon drop leg 23 and through the dryer journal for discharge through pipes 26 and 27, as the case may be, to the pressure differential control valve 29.

Delivery from the pipe is to the passageway 37 and the flow therein is in the direction of the arrows as indicated on Figure 4 vertically through the valve seat 35 at a rate of flow as determined by the position of the valve body 40 with relation to the valve seat 35; thence past the valve body 40 through the opening 36 and through passageway 38 to the discharge pipe.

The valve body 40 operates through gravity and a predetermined pressure differential across the valve seat 80

35 is fixed by the weight of the valve body 40, in relation to the area of the valve seat 35; it being understood that the valve body 40 is of a predetermined, definite mass. The purpose of the by-pass orifice 39 is to by-pass the valve body 40 with a constant fixed rate of flow of steam, or a mixture of steam and water for the double purpose of: (1) to maintain a constant circulation of steam through the dryer for the eviction of air and other non-condensable gases, and (2), to provide a continuous suction effect on the siphon inlet 24, so that, immediately the inlet 24 is condensate-sealed, ejection of the condensate is effected even though the valve body 40 may be in the closed position.

A further advantage, is that, with the valve body 40, in a closed position, the flow of condensate as effected by the by-pass orifice 39 will cause the condensate to build up in passageway 37 and the pipe with sufficient head pressure, which is additional to the pressure differential across the dryer, to lift the valve body 40 for discharge of the condensate.

As the prime purpose of the invention is to operate on a battery of dryers, and this means, that a multiplicity of pressure differential control valves 29 are operating individually to control the pressure differential between the steam header and the condensate header serving the battery, therefore, a slight variation in the operation of an individual control valve 29 could result in a valve being in a closed position, however, this can only be temporary, as the flow of condensate as induced by the by-pass orifice 39 will force the lifting of the valve body 40 in a matter of seconds.

The main condensate header 25 is connected by a drain pipe 46 to the inlet of a rotary discharge or like pump 47, and the outlet of this pump has connected therewith a discharge pipe 48 which leads back to the boiler plant. The secondary condensate header 28 enters into a uni-rate condenser 49, the outlet of which is connected by a pipe 50 to the drain pipe 46 adjacent to the inlet of the pump 47. Cooling water may be supplied to the uni-rate condenser 49 through a pipe 51. Air and other non-condensable gases and a very small amount of steam is discharged from the top of the uni-rate condenser 49 through a pipe 52 to a desired vacuum chamber or pump.

A by-pass pipe 53 is provided across the pump 47 from pipe 48 to pipe 46. The purpose of this pipe 53 is to by-pass sufficient condensate across the pump 47 to maintain a fixed level of condensate in the pipe 46, as shown by the dotted line indicated by the reference character 54, and this means, (1) a constant condensate head 54 in the pipe 46 plus the pressure in the condensate header 25, which provides the effective head in the intake of the pump 47; (2), a constant condensate head in the pipe 50, as indicated by the dot and dash line number 55, equal to the condensate head 54 in the pipe 46, plus the pressure differential across the dryers 12 and 13 and the baby dryer 14 as fixed by the pressure differential control valves 29.

An automatic liquid level controller 56 is provided for the by-pass pipe 53 and a control valve 57 is incorporated in the length of the by-pass pipe and is actuated automatically by the liquid level controller 56. The opposite ends of the controller are connected respectively to the pipe 46 above the head level 54 and to the by-pass pipe between the control valve 57 and the pipe 54.

From the foregoing description it can be seen that I have provided a novel heating and draining system for a battery of dryers which the latent heat in the stream is utilized to its fullest extent and in which a definite control is provided for each dryer of the battery of dryers.

Changes in details may be made without departing from the spirit or the scope of this invention, but what I claim as new is:

1. In a paper making machine, a battery of dryers including a primary section of dryers and a secondary section of dryers, means for circulating steam through the dryers of the primary section including a header for steam, means connecting all of the dryers of the primary section with the header, a header for condensate and returning steam for all of the dryers of the primary section, and a siphon for each of the dryers of the primary section including an outer drop leg pipe connected with the header for condensate and returning steam, and automatic means for maintaining a fixed predetermined pressure across each dryer of the primary

section including a gravity operated valve of a predetermined mass in the drop leg pipe of each siphon.

2. In a paper making machine, as defined in claim 1, and means for by-passing each valve for maintaining a constant minimum rate of flow of steam through the drop leg pipe of each siphon.

3. In a paper making machine, a battery of dryers including a primary section of dryers and a secondary section of dryers, means for circulating steam through the dryers of the primary section including a header for steam, means connecting all of the dryers of the primary section to the header, a header for condensation and returning steam for all the dryers of the primary section, a siphon for each of the dryers of the primary section connected with the header for condensation, and means for circulating steam and condensate from the last mentioned header to the dryers of the secondary section, means for removing condensate from the dryers of the secondary section, and automatic means for maintaining a fixed predetermined pressure differential across each dryer including a gravity operated valve of a predetermined mass.

4. In a paper making machine, a battery of dryers including a primary section of dryers and a secondary section of dryers, means for circulating steam through the dryers of the primary section including a header for steam, means connecting all of the dryers of the primary section with the header, a header for condensate and returning steam for all of the dryers of the primary section, a siphon for each of the dryers of the primary section including an outer drop leg pipe connected with the header for condensate and steam, means connecting all of the dryers of the primary section with the header for condensate and returning steam, a siphon for each of the dryers of the primary section for withdrawing condensate from said dryers and each including an outer drop leg pipe, a secondary header for condensate for said last mentioned drop leg pipe, and means disposed in the length of all of said drop leg pipes for the dryers of the primary and secondary sections for automatically maintaining a fixed predetermined pressure differential

across each dryer, and said last named means including a casing having communication at its opposite ends with sections of the outer drop leg pipes, a valve chamber in said casing including a lower valve seat and an upper escape port, a gravity operated valve of a predetermined mass slidable in the chamber for controlling flow of condensate vertically through the valve seat, and said casing having a passageway communicating with an upper section of pipe of the outer drop leg and valve seat and an outer passageway communicating with the escape port and a lower section of the outer drop leg pipe.

5. In a paper making machine as defined in claim 4, and means for by-passing the valve body for maintaining a constant minimum rate of flow of steam through the drop leg pipe of each siphon.

6. In a paper making machine as defined in claim 4, and means for by-passing the valve body for maintaining a constant minimum rate of flow of steam through the drop leg of each siphon and said last named means including a communication between the passageways directly above the escape port of the valve chamber.

7. In a paper making machine as defined in claim 4, and a sight glass carried by said casing in proximity to the valve chamber whereby the action of the valve body and the flow of condensate can be observed.

8. In a paper making machine as defined in claim 4, and a sight glass in said casing in proximity to the valve chamber whereby the action of the valve body and the flow of condensate can be observed, and means on said valve body against which the condensate impinges for turning said valve body.
